(57) **CLAIM**

The ornamental design for a wheel for automobile as shown and described.

DESCRIPTION

FIG. 1 is a front and left perspective view of a wheel for automobile showing my new design;

FIG. 2 is a rear and right perspective view thereof;

FIG. 3 is a front elevation view thereof;

FIG. 4 is a rear elevation view thereof; and

FIG. 5 is a left side elevation view thereof;

FIG. 6 is a right side elevation view thereof;

FIG. 7 is a top plan view thereof.

FIG. 8 is a bottom plan view thereof.

FIG. 9 is a reference view showing a part of another perspective view of a wheel for automobile in large scale; and,

FIG. 10 is a reference view showing a part of another perspective view of a wheel for automobile in large scale. The claimed portions of the wheel for automobile is indicated by the relatively dark portions, while the relatively light and blurred portions form no part of the claimed design.

1 Claim, 10 Drawing Sheets
